DECORATIVE ESCUTCHEON PLATE FOR SIDE- BOARDS, BUREAUS, AND THE LIKE

John J. Lubberts and Lambert J. Mulder, Grand Rapids,
Mich., assignors to Tomlinson of High Point, High
Point, N. C., a corporation of North Carolina

Application March 8, 1957, Serial No. 45,155

Term of patent 14 years

(Cl. D50—6)

FIG. 1

Fig. 1 is a front elevational view of a decorative escutcheon plate for sideboards, bureaus, and the like embodying our new design;

Fig. 2 is an edge view thereof; and

Fig. 3 is a rear elevational view thereof.

We claim:

The ornamental design for a decorative escutcheon plate for sideboards, bureaus, and the like, substantially as shown.
